UNITED STATES PATENT OFFICE.

HARRY J. COCKS, OF DES MOINES, IOWA, ASSIGNEE TO METAL PRODUCTS COMPANY, OF DES MOINES, IOWA.

FOOT ACCELERATOR.

Application filed November 5, 1926. Serial No. 146,419.

The object of my invention is to provide a foot accelerator of simple, durable and inexpensive construction.

It is one of the purposes of my invention 5 to provide such a foot accelerator which can be installed on a car as an accessory or installed in the factory during the original manufacture of the car.

Another object is to provide such a structure as will afford a positive actuation of the 10 throttle valve.

Still another purpose is to provide a foot accelerator having its parts so constructed and arranged as to afford direct and positive 15 connection between a foot actuated pedal or member and a throttle valve arm and to afford an auxiliary connection between the hand throttle control rod and the throttle valve of the carburetor, the parts being so arranged as to permit the control of the 20 throttle valve directly from the foot pedal without actuating the hand throttle but which will permit the use of the hand throttle in the ordinary way.

25 An additional object is to provide a foot accelerator and means for mounting it which will not involve such wear on the foot board of a car as will permit the parts to get out of adjustment or to bind.

30 Another object is to provide such an accelerator which is quick and easy to install.

Still another object of the present invention is to provide a foot accelerator which can be readily and easily attached upon any 35 Ford car employing the so-called Holley hot spot carburetor.

It is further my purpose to provide in such a foot accelerator, a number of novel features of structure in various parts of the 40 device.

An additional and special object of the present invention is to provide a structure so arranged that the foot accelerator portion may be operated without actuating the hand 45 accelerator portion and the hand accelerator portion may be operated without operating the foot accelerator portion.

With these and other objects in view, my invention consists in the construction, ar-

rangement and combination of the various 50 parts of my device, whereby the objects contemplated are attained, as hereinafter more fully set forth, pointed out in my claims, and illustrated in the accompanying drawings; in which:

55 Figure 1 is a perspective view of the foot accelerator.

Figure 2 is a similar view of a portion of another form of my accelerator which is the preferred form.

60 Figure 3 is a top or plan view of the portion of an automobile equipped with a foot accelerator, the dash being shown in horizontal section.

Figure 4 is a side elevation of the engine 65 equipped with a foot accelerator, the dash and floor board being shown in vertical section.

Figure 5 is an enlarged side elevation, parts of the device being shown in section 70 and parts being omitted, and taken on the line 5—5 of Figure 4.

Figure 6 is a detail sectional view of part of the mounting.

Figure 7 is a sectional view taken on the 75 line 7—7 of Figure 4, and

Figure 8 is a detail sectional view taken on the line 8—8 of Figure 5.

In the drawings herewith in which I have 80 illustrated my improved foot accelerator and portions of the automobile upon which it is installed, I have used the reference numeral 10 to indicate generally the engine of an automobile such as a Ford.

The engine has the intake manifold 11 85 and the exhaust manifold 12. The engine is equipped with what is known as the Holley hot spot carburetor which is indicated generally by the reference character A and has the float chamber 13; the hot plate 14 and 90 the air mixing chamber 10 in which is the throttle valve.

The throttle valve 15^a is of ordinary construction and has the stem 16 on which is the usual arm 17 and the projecting stop or 95 limiting lug 18. The arm 17 has at its upper end, the opening 19 from which projects the short sleeve 20 as shown in Figure 7.

Projecting from the arm between the hole 19 and the valve stem 16 is a flange 21 in which is mounted an adjustable stop screw 22. By actuating the arm 17 the throttle valve is controlled.

I have shown in order to illustrate the environment in which my accelerator is used, the car dash 23 and foot board 24. Extending through the foot board are the timer control rod 25, the steering rod 26 and the hand throttle control rod 27.

On the hand throttle control rod is an arm 28 as shown in Figures 3, 4 and 5. The parts just heretofore described are the usual equipment of the car and themselves do not form my present invention.

In the car as put out by the factory a connecting rod is extended between the arm 28 on the steering hand throttle control rod 27 and the throttle stem arm 17. This rod is indicated at 29 where my structure is connected with the arm 28 in the manner hereinafter to be described.

I will now describe my improved foot accelerator and explain the manner of its installation on the car.

I will describe first the means for actuating the throttle valve with the foot. I provide a bell crank lever 30 shown in Figures 1 and 4. This bell crank lever is pivoted on the carburetor in the following manner. The hot plate 14 is bolted in place by means of series of bolts 31.

One of these bolts is removed and inserted through a suitable bushing 31^a in one arm of the bell crank lever 30 as illustrated in Figures 1 and 6 to permit free swinging movement of the bell crank lever in a substantially vertical plane.

A foot control rod 32 has one end bent as at 33 and extends through the other end of the bell crank lever 30 as shown in Figure 1. A cotter pin 34 is put through the end 33 of the rod 32 to hold it against accidental removal.

Instead of being straight the rod 32 is bent to clear the adjacent parts of the engine and is extended rearwardly and upwardly through a suitable hole 35 and the floor board 24.

At its rear end the rod 32 is connected with a foot pedal which comprises a floor bracket 36 having the holes 37 to receive bolts or screws or the like 38^a for fastening it to the floor board. The bracket 36 has the parallel upstanding ears 38 receiving the pin or the like 39.

A foot pedal member 40 has a pair of downturned ears 41 at one end overlapping the ears 38 and having the pin 39 extending through them. The foot pedal 40 may be provided with a rubber pad 42 if desired.

At its forward portion it has a downturned ear or lug 43 provided with a hole 44

to receive an offset end 45 of the rod 32. 65 Through the end 45 is extended the cotter pin 45 for holding the rod in place.

The central portion of the bell crank lever 30 is connected with the valve stem arm 17 in the following manner. I provide a 70 special fitting which is shown best in its preferred form in Figure 2, comprising a plate 47 having a hole 48 to receive the sleeve 20 on the arm 17.

The plate 47 also has a pair of fingers 49 75 extending around the arm 17 for thus holding the plate against rotation on the sleeve 20. In the plate 47 is formed a curved slot 50. Pivoted to the central portion of the bell crank 30 is the offset 51 and end of the 80 rod 52. The other end of the rod 52 has an offset portion 53 extended through the slot 50 and bent over as at 54 to prevent accidental movement.

When the throttle valve is closed, the plate 85 47 will be in the position shown in Figure 2 and will hold the rod 52 at its upper limit of movement for thereby holding the bell crank lever 30 and the rod 32 in such position as to maintain the foot pedal 40 in 90 raised position.

When thereupon the foot pedal is pressed downwardly toward the foot board, it actuates the rod 32 longitudinally and rocks the bell crank lever on the bolt 31 for moving 95 the rod 52 and thus actuating the plate 47 and the throttle valve stem 17 for opening the throttle valve.

It will be noted, however, that nothing has been described so far to return the plate 100 47 and the arm 17 to valve closing position. The means for accomplishing this and the means for providing for hand throttle operation will be described, after first describing the slightly modified form of the device 105 shown in Figure 1.

In this foot accelerator instead of this plate 47 I use a fitting 55 which has a hole 56 similar to the hole 48 for receiving the sleeve 20 and has the fingers 57 for fastening the fitting 55 to the arm 17.

The fitting 55 has an offset finger 58 through which the bent portion 54 and the offset portion 53 of the rod 52 are inserted as shown in Figure 1. When either form of my device is used, I provide a spring 59.

The hooked end 60 is secured to the central portion of the bell crank lever 30 as by extending it around the end 51 of the rod 52 and is securely anchored to some support as to the bolt 61, where the form of fitting shown in Figure 5 is employed and the connection between the rod 51 and the bell crank lever is pivotal instead of 115 120 125 slideable.

The spring 59 tends to hold the throttle valve in closed position as well as to hold the foot pedal 40 in raised position.

Where the plate 47 is used, the spring 59 serves to hold the foot pedal in raised position.

When the plate 47 is employed, it will be understood that the parts are so constructed and arranged that when the spring 59 is fully contracted and the foot pedal 40 is raised and the throttle valve is closed, the end 53 of the rod 52 will rest in the left hand end of the slot 50 as shown in Figure 2.

I will now describe the means for hand operation of the throttle valve and connection therewith and will describe the means for holding the throttle valve normally closed under pressure when the plate 47 is employed.

Extended through the arm 28 on the hand throttle rod 27 is a bolt or the like 62. I provide a bracket 63 having an offset arm 64 mounted on the bolt 62 as shown in Figure 1.

The offset portion 64 is in the same plane as the main body of the bracket 63. The bracket 63 is provided with an elongated slot 65. In the end of the bracket 63 opposite the offset portion 64 is a short flange 66.

A hand actuating rod 29 is provided with a bent end 68 extended through the hole 30, sleeve 20 and the hole 56. A cotter pin 69 holds the end 68 against accidental removal. The other end of the rod 62 is extended slightly through a hole 70 in the flange 66 (see Figures 1, 2 and 8) and terminates in a bent portion 71 projecting through the slot 65.

On the portion 71 is a washer 72, beyond which the cotter pin 73 is extended through such portion 71. To better hold the rod 40, 67 and guide it on the bracket 63, I provide a fitting in the form of a short plate 74 shown in Figures 1 and 8. This plate 74 has at one end a hole 75 through which the bent portion 71 is extended and has at its other end 45 the spaced fingers 76 receiving between them the rod 29.

The plate 74 is wide enough so that it will not slip through the slot 65. When the plate 47 is employed as a part of my foot accelerator and I prefer the form using it, I mount on the rod 29 between the flange 66 of the bracket 63 and the fingers 76, a coil spring 77 which tends to yieldingly hold the bent portion 71 at that end of the slot 55 nearest the arm 28.

The two forms herein described are the same except that in the preferred form I use the plate 47 and the spring 77 whereas in the other form I use the fitting 55 and omit the spring 77.

I will now describe the practical operation of my foot accelerator first in the preferred form and then in the other form.

It will be understood that the hand throttle control is ordinarily carried in position

where the throttle valve is closed. When the hand throttle control rod 27 is in this position the arm 28 thereon will be in the position shown in full lines in Figure 2 and as shown for instance in Figure 3 and Figure 5.

The spring 77 will then hold the rod 67 at the right hand limit of its movement as shown in full lines in Figure 2 and as shown in Figure 3 which will hold the 75 throttle valve closed with the plate 47 in the position shown in full lines in Figure 2.

When it is then desired to operate the throttle with the foot accelerator for opening the throttle valve and supplying more fuel to the engine, the driver presses his foot on the pedal 40. The rod 32 is then moved downwardly and forwardly thus imparting rocking movement to the bell crank lever 30.

The rod 52 is carried with the bell crank 35 lever 30 and its end 53 engaging the plate 47 in the left hand end of the slot 50 as shown in Fig. 2, pulls the plate 47 and the arm 17 to a throttle opening position. This, of course, moves the rod 67 longitudinally. 90

Such movement of the rod 67, however, imparts no motion to the hand throttle control rod 27 because of the usual cooperation of the hand throttle control lever and sector on the steering wheel but not here shown. 95

The tension on the spring 77 is not sufficient to slide the bracket 63 against the resistance of the sector on the ordinary hand throttle lever. When the pressure on the foot pedal 40 is released, the spring 59 100 moves the rod 67 from its dotted line position shown in Figure 2, to its full line position and thus actuates the throttle valve toward closing position. 105

If it is desired to operate the throttle valve from the hand control mechanism, it will be noted that when the rod 27 is rotated in the ordinary and well known way, the bracket 63 will be moved toward the left from its full line position shown in Figure 2, by the rocking of the arm 28 carrying with it the rod 67 and actuating the throttle valve toward open position. 119

The plate 47 will slide with relation to the rod 52 without actuating that rod and therefore without tensioning the spring 59 or effecting the foot throttle control mechanism other than the plate 47. 115

This feature of the operation of my device, I believe to be novel. 120

It is therefore, observed that my foot throttle control mechanism can be operated without rotating the rod 27 or affecting the arm 28 and that the hand throttle control mechanism can be actuated without affecting the foot control mechanism. 125

When the fitting 55 is used, the spring 77 is unnecessary. The operation of the accelerator is the same as that described for it 130

when the plate 47 is used excepting that the fitting 55 always moves with the rod 52 and when the pressure on the foot pedal is released the spring 59 not only raises the 5 foot pedal but also serves to actuate the rod 52 and the fitting 55 for closing the throttle valve.

I claim as my invention:

1. In combination with a carburetor having a mixture control valve lever, a throttle control rod having a throttle lever thereon and a rod connecting the levers, a foot accelerator comprising a foot pedal for actuating the valve lever, a slide member pivoted to said throttle lever, said slide member having a slot therein and a perforated ear on one end, the second rod being mounted slidably through the ear and in the slot and means for maintaining said end in the slot. 10
2. In combination with a carburetor having a mixture control valve lever, a throttle control rod having a throttle lever thereon and a rod connecting the levers, a foot accelerator comprising a fitting adapted to be secured to said valve lever whereby the fitting and the lever form a bell crank lever, a spring for actuating the fitting in one direction and a foot pedal for actuating it in an opposite direction, a slide member having a slot and a slot, said second rod extending from the valve lever through the slot and into the slot whereby the spring maintains the portion of the rod in the slot at one end thereof and actuation of the foot pedal will move that portion away from said end of the slot and means for pivoting said slide member on said throttle lever. 15
3. In combination with a carburetor having a mixture control valve lever, a throttle control rod having a throttle lever thereon and a rod connecting the levers, a foot accelerator comprising a fitting adapted to be secured to said valve lever whereby the fitting and the lever form a bell crank lever, a spring for actuating the fitting in one direction and a foot pedal for actuating it in an opposite direction, a slotted slide member pivoted to said throttle lever, said second rod having one end bent at substantially right angles and extending through the slot, a keeper between said rod and the slide member, said keeper having ears for encircling the rod and a perforated end to receive the bent end of the rod. 20
4. In combination with a carburetor having a mixture control valve lever, a throttle control rod having a throttle lever thereon and a rod connecting the levers, a foot accelerator comprising a fitting adapted to be secured to said valve lever whereby the fitting and the lever form a bell crank lever, said fitting having an enlarged opening and said valve lever having a hub which is received in said opening, ears on said fitting for encircling the valve lever, a spring for actuating the fitting in one direction and a foot pedal for actuating it in an opposite direction, a slide member pivoted to said valve lever, a second rod extending through the slot and into the slot whereby the spring maintains the portion of the rod in the slot at one end thereof and actuation of the foot pedal will move that portion away from said end of the slot and means for pivoting said slide member on said throttle lever. 25
5. In combination with a carburetor having a mixture control valve lever, a throttle control rod having a throttle lever thereon and a rod connecting the levers, a foot accelerator comprising a fitting adapted to be secured to said valve lever whereby the fitting and the lever form a bell crank lever, said fitting having an enlarged opening and said valve lever having a hub which is received in said opening, ears on said fitting for encircling the valve lever, a spring for actuating the fitting in one direction and a foot pedal for actuating it in an opposite direction, a slotted slide member pivoted to said throttle lever, said second rod having one end bent at substantially right angles and extending through the slot, a keeper between said rod and the slide member, said keeper having ears for encircling the rod and a perforated end to receive the bent end of the rod. 30
6. In a structure of the class described, the combination of a throttle valve, valve stem and arm thereon, with a bell crank lever pivoted at one end, a foot pedal pivotally supported at one end, a rod pivoted to the other end of the pedal and to the other end of the lever, a link pivoted to the bell crank between its ends and to the arm and a spring arranged to normally hold the pedal raised. 35
7. In a structure of the class described, the combination of a throttle valve, valve stem and arm thereon, with a bell crank lever pivoted at one end, a foot pedal pivotally supported at one end, a rod pivoted to the other end of the pedal and to the other end of the lever, a link pivoted to the bell crank between its ends and pivoted to the arm for limited sliding movement, means for normally holding the pedal raised, a hand throttle control rod, an arm thereon and means for operatively connecting said last arm with the valve arm and a spring arranged to normally hold the pedal raised. 40
8. In a structure of the class described, the combination of a throttle valve, valve stem and arm thereon, with a bell crank lever pivoted at one end, a foot pedal pivotally supported at one end, a rod pivoted to the other end of the pedal and to the other end of the lever, a link pivoted to the bell crank between its ends and pivoted to the arm for limited sliding movement, means for normally holding the pedal raised, a hand throttle control rod, an arm thereon and means for operatively connecting said last arm with the valve arm and a spring arranged to normally hold the pedal raised. 45

throttle control rod, an arm thereon and means for operatively connecting said last arm with the valve arm and a spring arranged to normally hold the pedal raised by

5 a yielding slidable connection.

9. In a structure of the class described, the combination of a throttle valve, valve stem and arm thereon, with a bell crank lever pivoted at one end, a foot pedal pivotally supported at one end, a rod pivoted to the other end of the pedal and to the other end of the lever, a link pivoted to the bell crank be-

tween its ends and pivoted to the arm for limited sliding movement, means for normally holding the pedal raised, a hand throttle control rod, an arm thereon, a bracket pivoted to said last arm having an elongated slot and a perforated flange, a rod connected with said first arm, extended through said perforation and having an end slidably mounted in said slot, and a spring tending to hold such end at one end of the slot.

15 Des Moines, Iowa, October 28, 1926.

20 HARRY J. COCKS.
